UNITED STATES PATENT OFFICE.

MARY GALLATIN HOPPIN, OF NEW YORK, N. Y.

BOOK-REST.

1,334,373.

Specification of Letters Patent. Patented Mar. 23, 1920.

Application filed April 13, 1916. Serial No. 90,952.

To all whom it may concern:

Be it known that I, MARY GALLATIN HOPPIN, a citizen of the United States, and resident of the city and State of New York, 5 have invented certain new and useful Improvements in Book-Rests, of which the following is a specification.

The object of my invention is to construct a rest for books, magazines, or the like, for 10 general use.

Figure 1 is a perspective view of my invention and Fig. 2 is a similar view of the modification thereof. Fig. 3 is a fragment of a perspective view of a further modification, and Fig. 4 is a plan view of the additional attachments shown in Fig. 3, which may be used in connection with my invention. Fig. 5 is a cross section through that 15 part of Fig. 2 marked with the arrow. 20 Similar lettering is used in all of the figures for similar parts.

The device is portable, light in weight and sufficiently simple and strong to withstand the wear and tear of constant use. The 25 movable parts of the book-rest can be easily manipulated, so that the book can be removed and opened at the desired place with slight effort from any position. It is especially adapted to fit over the knees when the user 30 is in reclining position, although it can be used as an ordinary book-rest or easel.

The device is constructed of wood, metal, or any material desired and is in the form of an easel, having a back consisting of 35 two supports or legs B, which may be connected and strengthened by a transverse bar J. These supports are connected at the top by means of screws, hinges or other means C to the front supports or legs A. These 40 supports are likewise connected for strengthening purposes by transverse bars J¹ and J² and a top bar J³. Somewhat toward the lower portion of the front support is placed a transverse bar E at right angles to the 45 front support and permanently attached thereto by means of small supports K. A swinging cross-piece D is attached to the front of this bar, which is hinged by means of hinges F, so that this bar can be turned 50 up in normal position, as shown in Fig. 1, or swung down at an angle, or turned down completely as shown in Fig. 2. In Fig. 2, the device is shown with the upper bar device. This is movable up and down 55 on the front supports A by means of a back transverse bar J⁴ and a front trans-

verse bar S, similar in construction to the lower transverse bar E. These are connected together so as to form a space at T permitting this portion of the device to slide 60 up and down the front legs A for the purpose hereinafter explained. To the transverse bar S, is attached a swinging bar L exactly similar to the lower swinging bar D, being hinged at F in the same way. The upper bar L works exactly the same as the lower bar D, except in the reverse fashion, that is it is turned down when employed and up when released. In the form shown in Fig. 65 2 we have the legs B, adjustable by means 70 of pull out arrangements at U.

The manner in which the device is to be used when the user is reclining is as follows. It is adjustable around the body of the user, reclining or sitting in bed, as the case may 75 be. The body of the user fits longitudinally between the supports A and B. At right angles to and underneath the lower transverse bar E the supports A and B press against the sides of the user, so that the device is 80 held in position by such pressure. Necessary adjustment is obtained by means of the chains G which can be made larger or smaller and where the form shown in Fig. 2 is used by means of the adjustable arrangement shown 85 at U. The lower bar D is swung down, the book opened in place and the bar turned up to fasten the book securely opened; when the reader desires to turn the pages the bar is again turned down, the page 90 turned, and the bar turned up again. In the form shown in Fig. 2 the lower bar D is swung down and the upper bar arrangement raised on the front legs until the space between the upper and lower rests approximates the height of the book V. The upper bar L is raised, so that the book or periodical may be placed in position. The book is then 95 opened at the required place and the lower bar D turned up and the upper bar L turned 100 down. This furnishes a simple and perfect method of keeping a book open at the desired place. When it is desired to turn the page the upper swinging bar is turned up and the lower one down, the page is turned 105 and the swinging bars turned in place again. In the modification shown in Figs. 3 and 4 fingers are attached to the lower bar D, which are folded behind the bar when the device is not used, but when in 110 use, they are raised, so as to press on the pages in the manner shown. This special

device is in two sections, O and N, being collapsible and attached at R and Q by means of flat rings Q and R and screws S to the hinged bar and rotating at P. Fig. 5 is a 5 cross section of a fragment or part of Fig. 2, at the point indicated by the arrow. The spring is shown at W and the upper arrangement slides on the front legs A by means of the space T between the bar S and the back support J⁴.

I have found that the device embodying my invention, can be adjusted to suit the position of the user by lowering or raising the position of the bar, by extending or 15 tightening the chain attachment and then permitting the supports to spread farther apart.

Having described my invention, what I claim is:

- 20 1. A book rest having two rear and two front supporting legs and an upper and a lower transverse shelf member, the front supporting legs carrying the lower shelf and the upper shelf which is slidably adjustable on the supporting legs, both shelves being provided with bars hinged thereto, the bars of the lower shelf being adapted to be
- 25

turned up and that of the upper shelf to be turned down so as to retain the book in open position.

2. A book-rest having two rear and two front supporting legs and an upper and a lower transverse shelf member, carried by the front legs, the upper shelf being slidably adjustable thereon, and the lower shelf being provided with a hinged bar adapted to be turned upward to retain the book in open position and turned downward to release the book.

3. A book rest having two rear and two front supporting legs and an upper and a lower transverse shelf member, the front supporting legs carrying the upper and lower shelves which are provided with bars hinged thereto, the bar of the lower shelf 45 being provided with fingers adapted to be turned up and the bar of the upper shelf being adapted to be turned down so as to retain the book in open position.

MARY GALLATIN HOPPIN.
